UNITED STATES PATENT OFFICE.

MICHAEL P. CREAHAN, OF PITTSBURG, PENNSYLVANIA.

CURTAIN-ROD.

SPECIFICATION forming part of Letters Patent No. 702,707, dated June 17, 1902.

Application filed April 29, 1901. Serial No. 58,018. (No model.)

To all whom it may concern:

Be it known that I, MICHAEL P. CREAHAN, a resident of Pittsburg, in the county of Allegheny and State of Pennsylvania, have 5 invented a new and useful Improvement in Curtain-Rods; and I do hereby declare the following to be a full, clear, and exact description thereof.

My invention relates to curtain-poles and 10 supports therefor.

The object of my invention is to provide a curtain-pole to which the curtain may be quickly secured without danger of tearing the same and at the same time a support for 15 such pole by means of which said pole may be lowered within easy reach of a person standing on the floor of the apartment, so that the curtain may be applied to the pole or removed therefrom without the necessity of a 20 ladder or other elevated support.

My invention comprises, generally stated, a curtain-pole having a series of spring-fingers adapted to retain the curtain when inserted between said fingers and the body of the pole; 25 and it further comprises swinging arms secured to the window-frame, the upper ends of said arms having the supports for the pole and means for locking said arms in their raised position, whereby when said arms are 30 unlocked they are adapted to swing forward and downwardly to a point within easy reach of the person standing on the floor of the apartment.

To enable others skilled in the art to make 35 and use my invention, I will describe the same more fully, referring to the accompanying drawings, in which—

Figure 1 is a view of a window equipped 40 with my invention. Fig. 2 is a side view of the same, the support being shown dotted in its lowered position. Fig. 3 is an enlarged detail of the means for locking the arms. Fig. 4 is an enlarged view of one end of the pole, showing the spring-finger in engagement with 45 the curtain.

The numeral 2 designates a suitable window-frame. To the sides of said window-frame are secured the plates 3 by means of screws 4. Pivoted to the plates 3 at 5 and 50 adapted to swing therefrom are the arms 6. These arms 6 may be formed of strips of

metal or other suitable material. Through coincident openings 7 in the plates 3 and arms 6 the screws 8 pass, said screws acting to lock the arms 6 to said plates and hold said arms 55 in their vertical positions. By withdrawing the said screws 8 sufficiently to free them from the openings in the plates 3 it is apparent that the arms 6 will then be free to swing outward and downward, as will more fully 60 hereinafter appear. The upper ends of the arms where formed of one piece of metal are bent to form the brackets 9, adapted to support the pole 10, braces 18 being employed for purposes of strength. Connected to an 65 eyelet 12 on the pole 10 is the cord 13, which passes over pulleys 14 to a point at one side of the window.

The pole 10 is provided with a series of spring-fingers 15, said fingers being formed 70 of metal of suitable resiliency and being secured at one end by the screws 16. The free ends of said spring-fingers are bent up, as at 17, which permits of the material being readily inserted under said fingers, while at the 75 same time it enables the operator to lift the fingers without difficulty when it is desired to release the curtains. The fingers 15 are arranged longitudinally of the pole, and where there are two curtains suspended from the 80 pole, as shown, one half of the fingers for one curtain will have their free ends extending in one direction and the other half in the other. This arrangement permits of the folds of the curtain being arranged with greater nicety. 85 It is only necessary to lift the free end of the finger and slip the fold of the curtain under, when the strength of the spring will grasp the material and hold it securely without biting into the same so as to tear or stretch the 90 curtain. These fingers are preferably located on the front of the pole, so that when the curtain is secured thereby the curtain extends straight up beyond the pole, so that the pole is behind said curtain. 95

When my invention is in use and it is desired to lower the supports to attach the curtains to the rod, the screws 8 are turned sufficiently to free the arms, when by means of the cord 13 the supports may be lowered, the 100 weight of the outwardly-extending supports and pole causing the arms to swing outwardly

and downwardly, as shown in dotted lines, Fig. 2. In this manner the pole is lowered until within easy reach of the person standing on the floor below. It is then an easy 5 matter for the said person to apply the curtains to the pole, whether said pole is provided with the spring-fingers of my invention or other fasteners. When the curtains have been secured to the pole, the supports are 10 raised by the cord until at their proper position, when the screws 8 are tightened up so as to engage the plates 3 and hold the arms 8 in their vertical position.

By my invention the inconvenience of having 15 to stand on ladders or chairs to remove the curtains or secure them in place is avoided, while at the same time the spring-fingers enable the curtain to be inserted neatly with the folds in regular order and without liability 20 of the tearing or stretching of the curtains.

What I claim as my invention, and desire to secure by Letters Patent, is—

In combination with a curtain-pole, a series of spring-fingers rigidly attached at one end to the pole, the other end of said fingers being free and being curved outwardly from the pole, all of the fingers extending in longitudinal alinement with the pole and some of the fingers having their free ends extending in one direction and others in the opposite direction, said fingers adapted to engage intermediate of their ends with the fold of a curtain and clamp the same to the pole, substantially as described.

In testimony whereof I, the said MICHAEL 35 P. CREAHAN, have hereunto set my hand.

MICHAEL P. CREAHAN.
